(57) **CLAIM**

The ornamental design for a sink, as shown and described.

DESCRIPTION

In a preferred embodiment, the nature of this product is as a plumbing fixture primarily useful for washing various objects.

FIG. 1 is a left, top, front perspective view of a sink embodying our new design;

FIG. 2 is a top plan view thereof;

FIG. 3 is a front elevational view thereof, the rear elevational view being identical to the front elevational view shown;

FIG. 4 is a left side elevational view thereof, the right side elevational view being identical to the left side shown;

FIG. 5 is a cross-sectional view thereof taken along line 5—5 of FIG. 2; and,

FIG. 6 is a bottom plan view thereof.
